UNITED STATES PATENT OFFICE.

GEORGE ORVILL TERRY, OF MINNEAPOLIS, MINNESOTA.

SPARK-PLUG.

1,009,867.

Specification of Letters Patent. Patented Nov. 28, 1911.

Application filed April 3, 1911. Serial No. 618,536.

To all whom it may concern:

Be it known that I, GEORGE ORVILL TERRY, a citizen of the United States, residing at Minneapolis, in the county of Hennepin and State of Minnesota, have invented certain new and useful Improvements in Spark-Plugs; and I do declare the following to be a full, clear, and exact description of the invention, such as will enable others skilled in the art to which it appertains to make and use the same.

This invention relates to improvements in spark plugs for internal combustion engines and more particularly to improvements in what may be termed jump spark igniting plugs.

The object of the invention is to provide a simply constructed plug having a large smooth sparking surface and so constructed as to reduce the danger of short circuiting to the minimum.

Another object of the invention is to provide a plug of this character in which the electrodes are spaced the same distance at all points to permit the current to jump across at any point of the periphery of the center electrode.

Another object is to provide interchangeable electrodes by the use of which the life of the plug is greatly prolonged and the expense of providing extra plugs is avoided.

With these and other objects in view, the invention consists of certain novel features of construction, and the combination and arrangement of parts as will be more fully described and claimed.

In the accompanying drawings:—Figure 1 represents a side elevation of a plug constructed in accordance with this invention; Fig. 2 is a central longitudinal section thereof; Fig. 3 is an inner end view of the plug; Fig. 4 is a horizontal section taken on the line 4—4 of Fig. 2 looking in the direction of the arrow. Fig. 5 is a perspective view of one of the annular electrodes detached.

In the embodiment illustrated, an externally threaded metal shell 1 is shown adapted to be removably secured in the tapet hole or opening therefor in the cylinder of an explosive engine, as will be readily understood by those skilled in the art. This shell 1 at its outer end is externally formed as shown at 2 to receive a wrench or other implement whereby the plug may be rotated when screwing the same into or from

the cylinder. The outer portion of the internal longitudinal bore of the shell 1 is enlarged and threaded thereby forming an intermediate annular internal shoulder 3 60 from which the reduced portion of the bore extends to the inner end of the shell. At its inner end this shell is preferably formed on its inner face with an annular groove 4 which is preferably V-shaped in cross section and is designed to receive the ground electrode to be described. The inner edge of this end of the shell is preferably beveled as shown at 5 to facilitate the insertion of said ground electrode.

An elongated tubular insulating plug 6 is arranged in said shell and is composed of any suitable material such as porcelain, fiber, or the like. This insulating plug 6 is formed to longitudinally and removably enter a bore of the shell 1 and to be held therein by a hollow nut 7 through which the insulating plug loosely extends and which screws into the threaded outer end of the bore of shell 1 and forces the insulating plug inwardly in the shell by its engagement with an annular shoulder 6' formed on said plug intermediately of its ends. This nut holds the insulating plug at its limit of inward movement preferably against a 85 packing or cushioning ring 8 seated against the shell seat or shoulder 3. This packing ring 8 surrounds the reduced inner portion of the skirt of the insulating plug and is seated against the flared or inclined annular 90 exterior shoulder 9 formed on said plug at a point below the shoulder 6'. This packing may be formed of asbestos or any suitable material. The reduced inner end portion of the insulating plug 6 forms an annular 95 skirt 10 arranged concentrically within the reduced portion of the bore of the shell and terminates short of the inner end of the shell and forms an annular fluid compression chamber within the shell around said 100 skirt which extends from the open inner end of the shell longitudinally thereof to the packing washer 8. The longitudinal bore of the plug 6 extends throughout the length thereof and the inner end of this 105 bore is enlarged, the side walls thereof being preferably flared to form a compressed fluid cavity or chamber 11 open at the inner end of the plug and forming the hollow interior of the skirt 10 terminating at the intermediate internal annular seat or shoulder 12 within the plug.

A conducting stem or rod 13 screw threaded throughout the greater portion of its length extends through the bore of the insulating plug 6 and projects beyond the ends thereof, a disk 14 being secured to this inner projecting end and carrying the high tension electrode to be described. This stem 13 is provided intermediately of its length with a longitudinally adjustable stop nut 15 which co-operates with the internal shoulder 12 of the plug to limit the outward movement of the stem in the plug. This stem 13 is held in place by a cap 16 removably fitted on the outer end of the insulating plug 6 and screwed on the projecting end of the stem 13. The outer end of this stem 13 extends some distance beyond said cap to receive certain elements hereinafter to be described.

20 A shell 17 constructed of pressed fiber or other insulating material telescopically engages the upper portion of the insulating plug 6 and is exteriorly screw threaded at its lower or inner end and engages with 25 the interior thread on the outer end of the shell 1 outside the nut 7 and is securely locked in position thereon by nuts 18 and 19 secured on the outer end of the stem 13 which projects through an aperture in the 30 outer end of the shell 17, said nuts being designed to hold the shell 17 rigidly connected relatively to the insulating plug 6. This shell 17 is designed to serve as a protecting device and to doubly insulate the 35 conducting stem or rod 13.

Suitable packing rings 20 and 21 are arranged around the plug 6, the ring 20 being arranged between the outer face of the nut 7 and the inner end of the shell 17 and the 40 ring 21 between the inner face of the nut 7 and the shoulder 6'. These packing rings 20 and 21 provide for the expansion and contraction to which these plugs are subjected owing to the extreme changes in the 45 temperature to which they are exposed. The nuts 18 and 19 are also designed to serve as binding nuts by which the electric conductors from the magneto, vibrating coil box or other suitable source of high frequency 50 electric current, while the return current is made through the shell and engine cylinder as usual or in some other suitable manner. The nut 7 is preferably provided in its outer edge with a plurality of notches as 55 shown at 7' in Fig. 4 which are designed to receive a specially constructed wrench to provide for the turning of the nut below the outer edge of the shell 1.

The ground terminal 22 is constructed 60 from non-corrosive wire in the form of a split ring and is designed to be seated in the groove 4 formed in the inner face near the inner end of the shell 1, said ring being slightly larger than the groove in which it 65 is designed to be seated to cause it to spring

tightly into place and the beveled edge 5 of the shell 1 facilitates the insertion of said electrode.

The disk 14 is provided with a peripheral groove 23 preferably V-shaped in cross section and forms a seat for the high tension electrode 24 which is also constructed of non-corrosive wire in the form of a split ring which is a trifle smaller than its seat to cause it to spring tightly into place, the 75 resiliency of the ring holding it securely within the V-shaped groove 22. This disk 14 is also preferably provided with two or more recesses 14'' in its outer face to provide for the insertion therein of an instrument to hold said disk against turning while the nuts at the other end of the rod are being tightened. This disk 14 is adjustable by means of the threaded rod 13 to which it is fixed and such adjustment provides for the projection of the disk beyond the shell 1 to permit ready changing of the electrode 24 and also to vary the position of the disk relatively to the skirt 10 and the electrode 22.

The electrodes being annular in shape and constructed from wire of a gage that will provide the proper space between the two electrodes when placed in the plug and properly adjusted, the distance between said electrodes will be equal at all points and permit the current to jump across from one to another at any point on the periphery of the center electrode. As the circumference is a little greater than three times the diameter, 100 a large sparking surface will be obtained. These ring-shaped electrodes are also interchangeable rendering it possible to change them at any time thereby extending the life of the plug and avoiding the expense and trouble of being constantly provided with 105 extra sets of plugs.

By employing curved surface electrodes of such formation as to produce an annular spark gap of uniform width throughout, 110 the potential between the two electrodes will be approximately equal completely around the spark gap for the production of an electrical discharge across said gap consisting of a plurality of sparks distributed 115 around the gap. A condenser effect is produced by forming the opposing surfaces of the electrodes curved or rounded and smooth, that is, without angular or sharp edges, points, projections or roughness. 120 When the opposing electrode surfaces are thus smooth and curved the sparks can jump in either direction across the spark gap, and the electrical energy is stored or held back to attain the high potential necessary to produce an exceedingly "rich" electrical discharge of high caloric value and efficiency for ignition purposes. I find that peculiarly advantageous results and increased efficiency are attained in the oper- 125

ation of internal combustion engines by the employment of spark plugs or ignition devices embodying electrical condensers composed of the opposing electrodes and the intervening igniting spark gaps. With such a condenser, a spark gap of the desired width can be attained and even with an excess of oil and carbon on the condenser electrodes the exceedingly "rich" sparks 5 are given off and the intensity thereof seems to be increased by the presence and combustion of the oil and carbon.

To form the electrical condenser, the opposing surfaces of the electrodes are rounded or curved and all fine points or roughness which might permit current leakage and thus prevent the condenser action on said surfaces, are removed. In the example shown, the two chambers formed in the shell 10 around and within the depending skirt 21 have annular outlets between the lower edge of the skirt and the opposing electrodes, and the out rush of fluid from these chambers on the ignition of the charge is 15 thus caused to sweep the lower edge of said skirt with a scavenging action as well as the electrode surfaces in passing through the annular spark gap. This outrush of fluid will tend to break and remove bridges of 20 carbon and oil that might form across the spark gap and aid in the combustion thereof by the exceedingly "rich" sparks produced by the condenser. The position of the high tension electrode 24 with respect to 25 the opposite electrode 22 and with respect to the end of the insulating skirt 10 may be

varied by separating the parts and changing the position of the stop nut 15.

From the foregoing description, taken in connection with the accompanying drawings, the construction and operation of the invention will be readily understood without requiring a more extended explanation.

Various changes in the form, proportion and the minor details of construction may 40 be resorted to without departing from the principle or sacrificing any of the advantages of the invention claimed.

Having thus described my invention, what I claim is:—

A spark plug comprising a shell having an annular groove formed at one end thereof, an electrode in the form of a split ring arranged in said groove with the inner face of said ring projecting beyond the edges 50 of said groove, a longitudinally adjustable disk mounted in said shell and of less diameter than the annular electrode secured in said shell, said disk having a peripheral groove, and an opposing electrode in the 55 form of a split ring mounted in the groove of said disk with its periphery projecting beyond the edges of said groove and spaced from said first-mentioned electrode.

In testimony whereof I have hereunto set 60 my hand in presence of two subscribing witnesses.

GEORGE ORVILL TERRY.
